UNITED STATES PATENT OFFICE.

HERBERT PERKS, OF COVENTRY, ENGLAND.

WINDSHIELD FRAME.

Application filed November 23, 1926, Serial No. 150,210, and in Great Britain November 24, 1925.

This invention relates to side screens and windows including windscreens and more particularly to those of the detachable type as used on motor vehicles between the hood 5 and body.

For the purpose of providing a weather proof joint between the window and its guides and to prevent rattle and vibration, it has been proposed to use channelling made 10 of india rubber strengthened in some cases by a metal reinforcement housed within the material of the channelling. In these cases the channelling is either fixed within the window guides or riveted to the frame of a detachable window, in which latter case it may also 15 be formed with a draught excluding flap and a central division for sliding windows.

The present invention is distinguished from such devices in that it has for its primary object to provide a new or improved 20 method of and means for trimming the frame, whereby the cost of production is very materially reduced and at the same time a more durable and efficient trimming obtained. An important advantage of the improved trimming is that it can be used 25 equally well with glass, celluloid or other transparent material.

According to this invention the improved 30 trimming, which is made of india rubber or the like, is formed so that it can be applied to the window frame without the need for stitching or riveting and is characterized by a tubular portion whereby the trimming 35 may be introduced onto the frame, either telescopically or in a lateral direction and so as in either case to completely enclose the frame members.

The improved trimming may be molded 40 in strips of uniform cross-sectional shape comprising a tubular middle part to receive the glass, celluloid or other transparent material; and a draught-excluding flap or extension.

In order that the invention may be clearly 45 understood and readily carried into practical effect reference is made in further describing the same to the accompanying drawings, wherein,

50 Figure 1 is a perspective view showing an application of the device.

Figure 2 is a similar fragmentary view of the trimming, drawn to an enlarged scale.

55 Figure 3 is a transverse sectional view taken on line 3—3 of Figure 1.

Figure 4 is a perspective view of the back of a sliding window showing an application of the device thereto.

Figure 5 is a perspective fragmentary view showing the trimming used with a sliding window.

Figure 6 is a transverse sectional view taken on line 6—6 of Figure 4.

Figure 7 is a like view taken on line 7—7 of Figure 4.

As will be seen from Figures 1 and 4 the improved trimming, which is made of india rubber or the like, takes the form of a strip having a uniform cross-section throughout its length. The strip may be readily produced in any desired lengths by a process of extrusion.

The strip comprises a tubular middle part 10 to receive the metal frame 11 of the screen or window, a channel section part 12 to receive the glass, celluloid or other transparent material 13 and a flap or extension 14, which when the trimming or strip is in position on the window frame, is at the outside and overlaps and presses by its own elasticity against the body rail and other adjacent parts to exclude draught.

Where the frame 11 is built up of separate members connected together by angle plates 15, Figure 4, at the corners, the strip 85 may be introduced onto said members by threading the latter through it in an end-wise direction. In this case the strip is cut into suitable lengths and mitered, the ends at the corners being subsequently cold vulcanized or otherwise joined together.

Where, however, the shape of the metal frame is suitable the strip or trimming, being flexible, can be applied thereto in one continuous piece.

In order to avoid any difficulty that may be experienced in applying the strip to the frame the tubular portion 10, which may be of any desired cross-sectional shape to suit that of the frame, may be cut through longitudinally at a suitable place, as for example, at that part adjacent the base of the channel section portion of the strip, as indicated by the dotted lines 16 in Figure 2. Alternatively, the cut may be made adjacent the flap 14 as indicated by the dotted lines 16 in Figure 5, in which case it can be readily closed by vulcanizing or otherwise after the trimming is fitted to the frame.

The channel section portion 12 of the strip 110

is formed slightly dovetail so as to receive the glass, celluloid or the like 13 with a close water and draught proof fit.

In some cases, as at the bottom edge of the 5 screen or window, the flap 14 may be supplemented or replaced by a solid or tubular beading adapted when the screen is in position of use to make a close water and draught proof contact with the body rail.

10 As will be seen from Figures 4 to 7 the channel section part 12 of the strip may be duplicated for use in connection with sliding windows, the two panel sliding in or occupying separate parallel channels.

15 It will be appreciated that the invention is equally applicable to the windscreens as to the side screens and windows of motor vehicles, that is to say, the glass screen would be carried by the channel section portion of 20 the improved strip applied to the uprights and base, instead of directly by these latter members.

By the employment of trimming of the kind herein described it will be seen that a 25 very considerable saving in labor is effected in that it entirely eliminates the large amount of sewing or riveting previously necessary apart from which it constitutes an ideal trimming where glass is used in place of celluloid.

Having now particularly described and ascertained the nature of my said invention

and in what manner the same is to be performed I declare that what I claim is:—

1. In a wind shield frame, the combination with a metal frame and a transparent panel, of an elastic covering for said frame comprising a central tubular portion of substantially rectangular cross section, an outwardly extending strip formed integrally 40 with the front wall of said tubular portion, said strip having its inner wall at substantially a right angle with the wall of said tubular portion and its outer wall reduced in thickness towards its edge, and a plurality 45 of spaced integral strips extending oppositely outward from said tubular portion to receive the outer edges of the transparent panel.

2. In a wind shield frame, the combination with a rigid metal frame and a transparent panel, of a ductile covering for said frame comprising a tubular portion to envelope said frame, a flap formed on said tubular portion in register with one of the 55 walls thereof, and a plurality of converging outwardly extending, tapered strips of lesser width than said flap oppositely formed on said tubular portion to receive said panel of transparent material, the entire covering being of integral construction.

In testimony whereof I have signed my name to this application.

H. PERKS.
